UNITED STATES PATENT OFFICE

PHILIP E. MATTHEWS, OF PLAINFIELD, NEW JERSEY, ASSIGNOR TO INTERNATIONAL MOTOR COMPANY, OF NEW YORK, N. Y., A CORPORATION OF DELAWARE

FLEXIBLE RADIUS ROD

Application filed August 21, 1929. Serial No. 387,309.

The present invention relates to spring suspensions for motor vehicles and embodies, more specifically, an improved form of suspension in which the load due to gravitational forces is carried by one set of springs and the driving torque is cushioned by an independent set of springs.

There has recently been developed a spring suspension in which the driving torque has been carried by an independent set of springs as set forth above, thus enabling the springs which carry the gravitational forces to be made lighter and more effective in cushioning the shocks transmitted between the axles and frames. This construction has been found to be highly serviceable and a preferred form thereof has been incorporated in a construction in which the driving torque has been cushioned through a suitable mechanism mounted between the frame and the upper ends of the radius rods.

In certain types of vehicles, the space between the frame and radius rod, within which such mechanism can be incorporated, is very limited and it becomes quite difficult to include a cushioning mechanism in this locality, of sufficient size and strength to answer the requirements of use.

The present invention embodies a mechanism which is placed between the lower end of the radius rod and the axle, the lower end of the rod floating with respect to the axle and connected thereto in such manner that relative movement therebetween is effectively cushioned. By placing a yielding mechanism at this point, it is frequently possible, in many types of vehicles, to house it within the standard parts constituting the elements of this portion of the vehicle. For example, the cushion mechanism may be included within the brake mechanism or may cooperate therewith to provide a more compact and rigid construction.

An object of the invention, accordingly, is to provide a spring suspension in which gravitational forces are carried by one set of springs, and driving forces are cushioned by a separate and independent set of springs.

A further object of the invention is to provide a spring suspension of the above charac-

ter in which the mechanism for cushioning the driving forces is mounted between the lower end of the radius rod and the axle.

A further object of the invention is to provide a mechanism of the above character in which the cushioning means for the driving forces is included in the brake mechanism, or mounted in such manner that it cooperates therewith.

Further objects, not specifically enumerated above, will be apparent as the invention is described in greater detail in connection with the accompanying drawings, wherein:

Figure 1 is a view in side elevation, showing one form of spring suspension in which the present invention has been incorporated.

Figure 2 is a view in section, taken on the line 2—2 of Figure 1, and looking in the direction of the arrows.

Figure 3 is a view in side elevation, showing an improved form of spring suspension in which the invention has been incorporated.

Figure 4 is a view in section, taken on the line 4—4 of Figure 3, and looking in the direction of the arrows.

Figure 5 is a view in side elevation, partly broken away and in section, showing a further modification of the present invention.

Figure 6 is a view of the cushioning mechanism shown in Figure 5, the cap of the housing therefor having been removed in the interest of clearness.

Figure 7 is a view in side elevation, showing a further modified construction.

Figure 8 is a view in section, taken on the line 8—8 of Figure 7, and looking in the direction of the arrows.

Figure 9 is a view in elevation, partly in section, showing a further modified construction.

Figure 10 is a view in section, taken on the line 10—10 of Figure 9, and looking in the direction of the arrows.

Figure 11 is a view in elevation, similar to Figure 9, and showing a further modification of the invention.

Figure 12 is a view in section, taken on the line 12—12 of Figure 11, and looking in the direction of the arrows.

Referring to the above drawings, a desig-

nates a frame member of a motor vehicle having an axle b and a wheel c . Spring d is secured to the axle by means of U-bolts d' and the ends of the spring are connected to the frame through links d^2 , thus affording a floating connection for the spring and axle. Spring d serves to carry the gravitational forces and does not receive any of the driving forces.

10 The driving torque is transmitted to the frame through a radius rod e and bracket e' , the upper end of the radius rod being secured to the bracket e' at e^2 . A block f is mounted upon the axle b and carries the bolts d' .
 15 Arms f' are formed on the block and extend in opposite directions. A rocker arm g is journaled on the shaft b and formed with an arm g' to which the radius rod e is connected at e^3 . Extending in the opposite direction, the rocker arm g is formed with an arm g^2 which carries seats g^3 .

19 Adjustable arms h are secured to the extremities of arms f' and are formed with spring seats h' . The arms f' extend outwardly and into the plane of rocker arm g in order that the seats h' upon the arms h may oppose the seats g^3 upon the arm g^2 . Between these seats springs i are mounted as clearly shown in Figure 1.

20 Since arm g rocks with respect to spring d , the driving force will be transmitted from the axle b through block f , either arm f' , corresponding arm h and spring i , rocker arm g , and radius rod e to the frame a . In 25 this manner, none of the driving forces will be impressed upon the spring d and the latter will serve to cushion only the gravitational forces, while the springs i will cushion the driving forces.

29 The construction shown in Figures 3 and 4 is somewhat similar to that shown in Figures 1 and 2, and includes a block j upon the axle b and formed with arms j' having upwardly extending bearings portions j^2 . A 35 rocker arm k is journaled upon the shaft b and carries spring k' , bolts k^2 serving to connect the spring to the rocker arm. Arm k^3 on the floating rocker arm k is connected to the lower extremity of the radius rod e and the remainder of the construction is 45 similar to that shown and described with connection to Figures 1 and 2. Since block j is fixed to the axle, the driving force will be transmitted from the axle to the frame through block j , either arm j' , spring k' , floating rocker arm k , arm k^3 , and radius rod e .

53 In the construction shown in Figures 5 and 6, the shaft b carries a squared section b' over which a carrier b^2 is mounted. This carrier is formed with recessed seats b^3 to receive blocks of yielding non-metallic material b^4 . Spring d may be secured to the axle b by means of a block d^3 which, in this instance, may be journaled upon the axle.

Radius rod l is formed with a housing l' in which seats l^2 are provided. These seats receive certain of the blocks of yielding non-metallic material and pins l^3 may be provided to strengthen the connection. These pins should be so mounted that relative rotation of the carrier b^2 with respect to the housing l' may take place. A cap l^4 is formed with seats l^5 , similar to the seats l^2 and is secured to the housing l' by bolts l^6 .

70 In the construction shown in Figure 5, the driving force is transmitted from the axle to the frame through carrier b^2 , blocks of yielding non-metallic material b^4 , housing l' , and radius rod l .

75 In the construction shown in Figures 7 and 8, the mechanism differs somewhat from the previously described construction. Frame a carries a main spring m which is secured thereto through links m^2 . The spring is secured to a block n which is fixed to the axle b . Arms n' may be provided on the block to serve as supports for the brake mechanism and an arm n^2 is provided to which the lower end of the radius rod e is 80 connected. A curved bearing surface o is secured on the spring m and engages an arm o' which is pivoted to the frame at o^2 . A cantilever spring o^3 is secured on the arm o' and the end thereof is received within a housing o^4 which may carry a block of yielding non-metallic material o^5 .

85 When the vehicle is loaded, bearing surface o engages the arm o' and the gravitational load is carried by spring o^3 . Driving force 90 is transmitted to the frame from an axle b , through arm n^2 and radius rod e , such driving force being cushioned by the spring m . Although the spring m does carry a certain amount of the gravitational load, it is not 95 designed to serve entirely in such capacity, the spring o carrying the load.

With reference to Figures 9 and 10, the axle b is mounted upon a bracket p , upon which the spring d is mounted. The bracket p is formed with a housing p' which carries a block of yielding non-metallic material p^2 and is recessed at p^3 . Journaled upon the axle b is a crank q having an arm q' which is secured to the radius rod at e^3 , and an arm q^2 , which is formed with a bearing surface received within the recess p^3 and block of yielding non-metallic material p^2 . This construction functions similarly to those described above and further description thereof is deemed unnecessary.

105 The construction shown in Figures 11 and 12 is somewhat similar to that of Figures 9 and 10, a bracket r being secured to the axle b and formed with similar housings r' having recesses r^2 and carrying blocks of yielding non-metallic material r^3 . A crank s , journaled on the axle b is formed with an arm s' which is connected to the end of the radius rod e , and similar arms s^2 which are received with- 110

in the blocks of yielding non-metallic material r^s . The construction shown in these figures operates in a manner similar to that of the construction shown in Figures 9 and 10.

5 While the invention has been described with specific reference to the constructions shown in the accompanying drawings, it is not to be limited, save as defined in the 10 appended claims.

I claim as my invention:

1. A spring suspension between a frame and an axle comprising a load carrying spring, means to mount the spring between 15 the frame and axle to serve only as a load carrying spring, a radius rod hinged positively to the frame, a second spring, a rocker arm floating on the axle and carrying the second spring, and an arm carried by the axle 20 for engaging the second spring.

2. A spring suspension between a frame and an axle comprising a load carrying spring, means to mount the spring between 25 the frame and axle to serve only as a load carrying spring, a radius rod hinged positively to the frame, a second spring, a rocker arm floating on the axle and carrying the second spring, and an arm carried by the axle 30 for engaging the second spring.

3. A spring suspension between a frame and an axle comprising a load carrying spring, means to mount the spring between 35 the frame and axle to serve only as a load carrying spring, a radius rod hinged positively to the frame, a second spring, a rocker arm floating on the axle and carrying the second spring, and means carried by the axle 40 for engaging the second spring.

4. A spring suspension between a frame and an axle comprising a load carrying 45 spring, means to mount the spring between the frame and axle to serve only as a load carrying spring, a radius rod hinged positively to the frame, a second spring, a rocker arm journaled on the axle and engaging the second spring, and means carried by the axle 50 for engaging the second spring.

5. A spring suspension between a frame and an axle comprising a load carrying 55 spring, means to mount the spring between the frame and axle to serve only as a load carrying spring, a radius rod hinged positively to the frame, a second spring, a rocker arm engaging the second spring and connected to the radius rod, and means carried by the axle for engaging the second spring.

6. A spring suspension between a frame and an axle comprising a load carrying 60 spring, means to mount the spring between the frame and axle to serve only as a load carrying spring, a radius rod hinged positively to the frame, a cushioning means, means to mount the cushioning means upon 65 the axle, and means associated with the other

end of the radius rod to engage the cushioning means.

7. A spring suspension between a frame and an axle comprising a load carrying spring, means to mount the spring between 70 the frame and axle to serve only as a load carrying spring, a radius rod hinged positively to the frame, a cushioning means, means to mount the cushioning means upon the axle, and means to hinge the other end of the radius rod positively upon the last 75 named means.

8. A spring suspension between a frame and an axle comprising a load carrying spring, means to mount the spring between 80 the frame and axle to serve only as a load carrying spring, a radius rod hinged positively to the frame, a cushioning means, means to mount the cushioning means upon the axle, and means to connect the other end 85 of the radius rod to the last named means.

This specification signed this 2d day of Aug., A. D. 1929.

PHILIP E. MATTHEWS.
